(57) **CLAIM**

The ornamental design for a combination dental floss and pick, as shown and described.

DESCRIPTION

FIG. 1 is a right side elevation view of a combination dental floss and pick showing my new design;

FIG. 2 is a left side elevation view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is an isometric view thereof;

FIG. 8 is an exploded isometric view thereof showing a pick separated from a dental floss body; and,

FIG. 9 is a cross-sectional view taken along line 9-9 of FIG.
